(57) **CLAIM**

(21) Appl. No.: **29/320,963**

The ornamental design for a spiral cut circle skirt in intercon-
necting spirals, as shown and described.

(22) Filed: **Jul. 8, 2008**

DESCRIPTION

(51) **LOC (9) Cl.** **02-02**

FIG. 1 is a perspective view of a spiral cut circle skirt in
interconnecting spirals, showing my new design;

(52) **U.S. Cl.** **D2/851**

FIG. 2 is a front elevational view of the invention;

(58) **Field of Classification Search** D2/851,

FIG. 3 is a rear elevational view of the invention;

D2/712, 852, 739, 781, 785, 790; 2/211;
D30/145

FIG. 4 is a left-side elevational view of the invention;

See application file for complete search history.

FIG. 5 is a right-side elevational view of the invention;

(56) **References Cited**

FIG. 6 is a top plan view of the invention, shown with a
portion of the skirt partially upturned condition; and,

U.S. PATENT DOCUMENTS

FIG. 7 is a bottom plan view of the invention.
